Primary Examiner — Steven J Czyz

(57) CLAIM

The ornamental design for a pill organizer, as shown and described.

DESCRIPTION

FIG. 1 is a front, right, top perspective view of a pill organizer showing my new design;
FIG. 2 is a back, left, bottom perspective view thereof;
FIG. 3 is an open state diagram of the pill organizer;
FIG. 4 is a front view thereof;
FIG. 5 is a back view thereof;
FIG. 6 is a left view thereof;
FIG. 7 is a right view thereof;
FIG. 8 is a top view thereof;
FIG. 9 is a bottom view thereof;
FIG. 10 is an enlarged view of the encircled area 10 of FIG. 1;
FIG. 11 is an enlarged view of the encircled area 11 of FIG. 4;
FIG. 12 is an enlarged view of the encircled area 12 of FIG. 8;
FIG. 13 is an enlarged view of the encircled area 13 of FIG. 8; and,
FIG. 14 is an enlarged view of the encircled area 14 of FIG. 9.

The broken lines shown on the drawings depict portions of the pill organizer that form no part of the claimed design.

1 Claim, 11 Drawing Sheets
